US00D760091S

(12) **United States Design Patent**
Pheir

(10) **Patent No.:** **US D760,091 S**
(45) **Date of Patent:** **** Jun. 28, 2016**

(54) **CONTAINER HAVING TRIANGULAR COMPARTMENTS**

(71) Applicant: **Hirshol H. Pheir**, St. Thomas, VI (US)
(72) Inventor: **Hirshol H. Pheir**, St. Thomas, VI (US)
(**) Term: **14 Years**
(21) Appl. No.: **29/517,510**
(22) Filed: **Feb. 13, 2015**
(51) LOC (10) Cl. **09-03**
(52) U.S. Cl. **USPC D9/756**

(57) **CLAIM**

The ornamental design for a container having triangular compartments, as shown and described.

DESCRIPTION

This application is related to the following co-pending applications filed concurrently herewith by the same Applicant: “Multi-Compartment Roll-Up Container” application Ser. No. 14/621,542, “Multi-Compartment Roll-Up Container-Rounded”, application Ser. No. 29/517,512, and “Multi-Compartment Roll-Up Container-Rounded Different Sizes”, application Ser. No. 29/517,514. The complete disclosures of these co-pending applications are incorporated herein by reference.

FIG. 1 is a top perspective view of a container having triangular compartments, showing our new design;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof; and,

FIG. 7 is a bottom plan view thereof.

1 Claim, 6 Drawing Sheets
